CLAIM

The ornamental design for a communication device with display as shown and described.

DESCRIPTION

FIG. 1 is a front perspective view of a communication device with display according to the present invention;

FIG. 2 is a rear perspective view of the communication device with display;

FIG. 3 is a top view of the communication device with display;

FIG. 4 is a bottom view of the communication device with display;

FIG. 5 is a left side view of the communication device with display;

FIG. 6 is a right side view of the communication device with display;

FIG. 7 is a rear view of the communication device with display; and,

FIG. 8 is a front view of the communication device with display.

The broken lines shown in the drawings represent portions of the communication device with display that form no part of the claimed design.

1 Claim, 5 Drawing Sheets
